UNITED STATES PATENT OFFICE.

JAMES S. MARTIN, OF DORMONT BOROUGH, PENNSYLVANIA, ASSIGNOR OF ONE-HALF
TO WILLIAM C. BOYD, OF MCKEES ROCKS, PENNSYLVANIA.

DUMP-CAR.

1,153,939.

Specification of Letters Patent. Patented Sept. 21, 1915.

Application filed July 21, 1914. Serial No. 852,268.

To all whom it may concern:

Be it known that I, JAMES S. MARTIN, a resident of Dormont Borough, in the county of Allegheny and State of Pennsylvania, have invented a new and useful Improvement in Dump-Cars, of which the following is a specification.

This invention relates to dump cars and more particularly to that type of dump car having a side-wise tilting body.

The purpose of the invention is to provide a dump car of the class named whereby greater lateral movement of the car body is obtained than by such cars as heretofore constructed, so that the load can be thrown farther from the track and prevented from falling back on to the track when dumping on level ground; which is easy to operate by an arrangement such that the center of gravity of the loaded body moves in a downward direction while dumping, while the center of gravity of the empty body also moves in a downward direction when righting the car body after dumping; which is of a lower construction than similar cars as heretofore constructed, thereby not only saving in cost of loading but making the car more stable and less likely to overturn when running; and which is adaptable to different conditions by variations in the construction.

The invention comprises a dump car of the character specified constructed and arranged as hereinafter described and claimed.

In the accompanying drawings Figure 1 is a vertical transverse section through the car showing the body in upright position; Fig. 2 is a similar view showing the body tilted for dumping; Fig. 3 is a side elevation of the car; Fig. 4 is a vertical central longitudinal section through the car; Fig. 5 is a vertical transverse sectional view of the car; Fig. 6 is a sectional detail view of the locking means for the doors or car sides; Fig. 7 is a detail view showing a modification of the door locking means; and Figs. 8 and 9 are views similar to Figs. 1 and 2 but showing a modified form of body and doors or sides.

The car comprises a tilting body 1 which is mounted for sidewise tilting upon a suitable frame. The frame illustrated comprises suitable longitudinal members 2 shown as I beams located at or near the sides of the car and which are joined by suitable

transverse members, of which the drawings illustrate a suitable body bolster 3, end sill 4 and one or more additional transoms or beams 5. At or near the ends of this underframe are suitable transverse upright frames 60 from which the car body is supported, these frames comprising vertical web plates 7 connected to the underframe by angle members 8 and having angle members 9 extending along their upper edges, and stiffened by 65 vertical angle members 10. A channel beam 11 is supported by suitable bracket members 12 near the top edge of each cross frame and is spaced slightly inwardly therefrom. These upright frames are braced by suitable 70 members 13 connecting the upright frames near their tops with the underframe. Various other constructions of supporting frames will readily suggest themselves.

The body comprises a suitable bottom 14 75 and ends 15, which may be constructed in any suitable way, the drawings showing the same formed of plate metal with the bottom plates strengthened by the side bars 16 which are shown as Z bars, and center 80 stringers 17 which are shown as I beams, while the ends 15 are connected to the bottom by angle bars 18 and are stiffened at their upper edges by similar bars 19. The sides 20 of the body are formed as swinging 85 doors, arranged when the body tilts to swing out of normal position and dump the contents. As shown in Figs. 1 to 4 these doors swing downwardly, being supported by a pair of links 21 and 22 at each end of the 90 door, which links at one end are pivoted respectively near the upper and lower edges of the door, and at their opposite ends are pivotally connected to the ends of the car body, these links being so arranged that 95 when the doors open they swing outwardly and downwardly and take a position substantially underneath the bottom of the body out of the way of the discharging load, as shown in Fig. 2. Suitable spring pressed 100 latches 23 are pivotally mounted on the ends of the car body and have hooked ends 23a arranged to engage the links 21 of the doors and lock them in closed position. These latches have their tails 25 so formed and arranged that when the body tilts said tails contact with posts or similar obstructions 26 on the end frames, to disengage said latches from the door and permit the latter to open.

The body is supported from the end 110

frames by means of links 27 and 28, whose upper ends are pivoted on suitable pins 29 and 30, respectively, at the upper edges of the upright frames and preferably between the upright plates 7 and the channel beams 11, while their lower ends are pivotally connected by means of pins 31 and 32 respectively, to brackets or frames 33, secured to the car body, and in the form shown in Figs. 1 to 4, depending a considerable distance downwardly from said car body. These bracket frames may be constructed in any suitable way. As shown they comprise web plates 34 having their edges strengthened by angle bars 35, and being braced by brace members 36 extending from near the lower edges of the depending brackets to the stringers 17 of the car body. Any other suitable construction of bracket may be employed.

The links 27 and 28 are shown with their upper ends spaced farther apart than their lower ends, so that when the car body is moved sidewise the lower pivotal end of one link moves in an upwardly extending arc, shown at 37, while the lower pivotal end of the other link moves in a downwardly extending arc, as shown at 38, as a consequence of which the car body is tilted, shown in Fig. 2. It will be further observed that when moving from the position shown in Fig. 1 to that shown in Fig. 2 the link 28 has swung toward the right to the farthest extent when the pivotal point 31 lies in the line 39 connecting the pivotal points 29 and 32, and that the further sidewise movement of the car body causes the pivotal point 32 to swing backwardly, that is, toward the center of the car, while the pivotal point 31 continues its upward swing. This link arrangement is such that when the car body tilts it swings decidedly toward one side, and consequently the load is deposited some distance beyond the track, so that it does not flow back onto the track as readily as with present types of side dumping cars. The arrangement shown is such that as it swings to tilting position the center of gravity of the loaded body lowers, while in the final tilted position the center of gravity of the empty body is somewhat higher than when the empty body is in righted position, so that in righting the car body its center of gravity is again lowered. As a consequence, the movement of the car body to tilt and to right is effected with the expenditure of a minimum amount of power.

By varying the lengths of the links 27 and 28, or varying the distances between the upper and lower ends respectively of the pair of links at each end of the car, the body can be tilted to any desired angle, depending upon the character of material to be handled,—so as to insure the discharge of the material from the tilted body. The lower

ends of the links may be connected directly to the car body, or to a downward depending bracket, or even to an upward projecting bracket, depending upon the character of car body and the length and arrangement of the supporting links.

The car body can be moved by any suitable mechanism, either hand power, or compressed air power, or the like. The drawings show one simple arrangement for this purpose, this comprising a crank shaft 40 mounted in a bracket 42 extending from the top of one end of the car body and carrying a pinion 43 which engages a rack 44 secured to the top of the upright cross frame, and which rack is of such shape or contour that the pinion engages the rack during the entire swinging movement of the car body.

The opening movement of the doors 20 is controlled by means of vertical cam tracks or guides 45 secured to the frame of the car at each of the vertical upright frames, and which are engaged by rollers 46 journaled on the lower edges of the doors at each end. When the car body is righted these rollers also engage with said guides and the latter are so shaped that they swing the doors to closed position, whereupon they are automatically locked by the latches 23. In closed position of the doors the rollers 46 rest on the upper edges of the cams 45, which therefore assist in supporting and holding the doors in closed position. In the case of long car bodies it may be necessary to also support the body between its ends. This is accomplished by providing the car body intermediate its ends with depending brackets 48 having at their lower ends rollers 49 which run on guides or tracks 50 on a transverse transom 51 of the car frame. In the case of short cars this intermediate support is not necessary.

Fig. 7 shows a modification of the locking means for the car side or door. In this modification the latch 23^a engages a pin 24^a on the link 21, and said latch is provided with a roller 26^a bearing on the top of the transverse upright frame so that as the car body moves outwardly this roller and the latch are lifted sufficiently to disengage the hook of the latch from the pin 24^a to release or unlock the car side.

Figs. 8 and 9 show the car body somewhat deeper than shown in Figs. 1 and 2, and with the depending brackets 33 of less depth than in Figs. 1 and 2. They also show the sides or doors 20 arranged to swing upwardly, instead of downwardly. As here shown the position of the links is reversed from those shown in Figs. 1 and 2, namely, the link 22^a connects to the upper edge of the car side while the link 21^a connects to the lower edge of said car side. This side is actuated by means of a lever 53 fulcrumed at 54 on the end 15 of the car body and having its upper

end connected by the link 55 to the link 21^a and its lower end connected by slotted link 56 to one of the supporting links 27 or 28. On the side which is lowered, (to wit, the 5 right side, Fig. 9) these links and pivoted lever act to swing the car side or door 20 upwardly and outwardly at its lower edge, while on the opposite side of the car the slot in link 56 provides sufficient lost motion so 10 that the door or side 20 on that side of the car remains in closed position. In order that the car sides or doors shall clear the body when swinging it is necessary that the pivotal point of attaching the link 22 or 22^a, 15 namely the point 58, shall be slightly below (in the case of Figs. 1 and 2) the lower edge of the door, or slightly above (in the case of Figs. 3 and 9) the upper edge of the door. The sides or doors 20 when opening 20 have their upper edges moving in one arc while their lower edges move in an oppositely inclined arc, as will be readily apparent from a comparison of Figs. 1 and 2 and Figs. 3 and 9, respectively. Various other 25 arrangements for mounting the swinging sides of the car body can be provided without departing from the invention.

The car described can be built up in any 30 suitable way and from any suitable material, and the specific construction of the frame and car body illustrated and described does not constitute the essence of the invention as defined in the claims hereinafter made.

The advantages of the car construction 35 described as compared with previous cars of a similar type are (1) that the body has a greater lateral movement so as to throw the load farther from the track (2) the ease of operation due to the fact that the parts are 40 so arranged that the center of gravity of the loaded body moves in a downward direction during dumping, while the center of gravity of the empty car body also moves in a downward direction when righting; (3) a lower 45 construction as a whole so as to save cost of loading, and also making the car more stable and less likely to overturn when running over rough track; and (4) the adaptability 50 of the design to different conditions because the principle of construction allows a large number of variations in order to meet different conditions of use.

What I claim is:

1. A dump car, comprising a frame, and 55 a side dumping body mounted in said frame in such manner that when moving to dumping position a point on one side of the longitudinal center of said body moves in an upwardly extending arc around a center on the same side of the body and a point on the opposite side of the longitudinal center of the body moves in an independent and downwardly extending arc around a corresponding center on its side of the body, the sides 60 of the car body being so arranged that the

downwardly moving side drops down and under the car body as it tilts.

2. A dump car, comprising a frame, a side dumping body, and a pair of links at each end of said body, each link at one end 70 being pivotally connected to a point on one side of the body and at its opposite end being pivotally connected to a point on the same side of the frame, said links being so arranged that when the car body is swung 75 thereon one side moves downwardly and the other side moves upwardly, the sides of the car body being so arranged that the downwardly moving side drops down and under the car body as it tilts.

3. A dump car, comprising a frame, a side dumping body, and a pair of links at each end of said body, the links of each pair being free of connection to each other and lying on opposite sides of the longitudinal 85 center of the car, said links at one of their ends being pivotally connected to the body and at their opposite ends being pivotally connected to the frame, the links at each end of the car body being inclined in opposite 90 directions, whereby when the car body is swung one side moves upwardly and the other side moves downwardly, the sides of the car body being so arranged that the downwardly moving side drops down and 95 under the car body as it tilts.

4. In a dump car, a side dumping body, 100 movable sides for said body, and links connecting two points near the top and bottom edges of said sides to said body and so arranged that the top and bottom edges of 105 said sides respectively move in independent arcs around centers on the ends of the car body, each said center being on the same side of the longitudinal center of the car body as the arc described around said center, one arc extending outwardly from the car body, and the other arc extending inwardly from the car side.

5. In a dump car, a side dumping body, 110 movable sides for said body, means for connecting said sides to said body so arranged that the top and bottom edges of said sides 115 respectively move in independent arcs, the upper edge of the side moving outwardly and downwardly, and the lower edge of the side moving inwardly, whereby the side drops down and under the car body.

6. In a dump car, a side dumping body, 120 movable sides for said body, and a pair of links at each end of a movable side, one end 125 of each link being pivotally connected respectively near the upper and lower edges of the sides, and the other ends of the links being pivotally connected to the car body, the last named ends of said links being closer together than the first named ends thereof.

7. In a dump car, a side dumping body, a 130 movable side for said body, and a pair of

links at each end of said side, one of said links having one end pivotally connected near the lower edge of the car side, and the end of the other link being pivotally connected near the upper edge of said side, the opposite ends of said links being pivotally connected to the car body at points lying in different horizontal and vertical planes and the car end of the first named link lying below the car end of the second named link, whereby when the side is swung its opposite edges move in independent arcs and the side moves under the car body.

8. In a dump car, a side dumping body, movable sides therefor, links connecting said sides to the car body so arranged as to permit the sides to swing to open and closed positions with the sides under the car body in open position, and cam members on the car frame arranged to be engaged by said swinging sides to guide the same in their

opening and closing movements and to also support said sides in closed position thereof.

9. A dump car, comprising a frame, a side dumping body, and a pair of links at each end of said body, each link at one end being pivotally connected to a point on one side of the body and at its opposite end being pivotally connected to a point on the same side of the frame at an elevation above the bottom of the car body when in normal position, said links being so arranged that when the car body is swung thereon one side moves downwardly and the other side moves upwardly.

In testimony whereof, I have hereunto set my hand.

JAMES S. MARTIN.
